UNITED STATES PATENT OFFICE.

ARTHUR McDougall DUCKHAM, OF LONDON, ENGLAND.

FURNACE FOR PRODUCING CHEMICAL CHANGES.

Application filed December 28, 1921. Serial No. 525,455.

To all whom it may concern:

Be it known that I, Sir ARTHUR McDougall DUCKHAM, a subject of the King of Great Britain, residing in London, England, have invented certain new and useful Improvements in Furnaces for Producing Chemical Changes, of which the following is a specification.

In the heating of substances for promoting chemical change it is frequently desirable that the process should be carried out continuously in a closed furnace.

For this purpose I construct an annular muffle furnace containing a travelling platform or the like, in such a manner that the muffle is completely closed and the material is charged into and discharged from the muffle without interrupting the operation of the furnace.

The material to be heated is conveyed in the muffle on trucks or an annular platform of a kind known in annular furnaces or kilns, but preferably constructed so that the material may be distributed on the carrying surface so as to be in close proximity to the heated roof of the muffle which roof radiates heat on to the material.

The charging of the material may be by means of a gas-tight feeding device and chute, and a vertically adjustable striking plate in front of the charging chute, in the direction of travel of the material, may determine the thickness of layer and the mode of distribution of the material on the carrying surface. It is advantageous that the charging device should be as far removed as may be from the hottest zone of combustion in the furnace. The discharging or removing device is preferably immediately behind the charging device and may consist of a bucket conveyer or the like which removes the material that has been piled up by an adjustable scraper which may be set to remove the whole of the material or only the upper portion of the layer. When trucks are used the scraping device may be set at an angle to the path of the trucks, the material being thus transferred from the truck surface to the side of the muffle and discharged through a chute which is closed by a gas-tight discharging device. The charging and discharging may be continuous or may be timed to occur only after a certain number of revolutions of the carrying surface.

By the proper arrangement of heating flues, heat can be applied to the material over substantially the whole or any desired portion of its travel through the muffle.

Suitable ports may be arranged through the roof or walls of the muffle for admission of any desired gas or other agent or for escape of elastic fluid.

In the accompanying drawings, Figs. 1 and 2 are developed longitudinal vertical sections through a furnace constructed according to this invention and shown in sectional plan drawn to a reduced scale in Fig. 9. Fig. 3 is a cross section of line 3-3 of Fig. 1 and Figs. 4, 5, 6, 7 and 8 are cross sections respectively on lines 4-4, 5-5, 6-6, 7-7, 8-8 of Fig. 2.

Referring to Fig. 9, the furnace is constructed of concentric walls *a* at the centre of which is a chimney *b* connected with the furnace through a flue *c* shewn in dotted lines. The walls are carried on girders *d* supported on piers *y* (Figs. 1, 2 and 3) and the space between the inner of these girders is closed by plates *d*¹ (Figs. 5 and 8). At equiangular distances apart the plates carry depending pockets *d*² (Figs. 3 and 4) which contain bearings for rollers *e*. On the latter are supported the flanges of an annular girder *f* carrying an annular platform *g* constructed of hollow brickwork filled with concrete *g*⁴, and the upper surface of the platform is formed as a shallow trough having its bottom *l* of convex cross section of radius similar to that of the roof *h* spanning the space between the walls *a* and forming with these and the plates *d*¹, the muffle chamber.

The girder *f* carries a rack *f*¹ which is in gear with a suitably driven pinion *f*² (Fig. 7) so that the platform is continuously rotated.

The material (in this case a pulverulent solid) is fed continuously into the trough of the platform through a gas-tight feeding device *g*³ and a chute *g*¹ (Fig. 4) at a part of the muffle which is not heated by the flues presently to be described. The direction of travel being that shown by the arrow in Figs. 1 and 2, the forward side of the chute *g*¹ carries an adjustable plate *g*² (Fig. 2) which serves to determine the depth of the layer of material in the trough.

The roof *h* of the muffle is heated by combustion of gases in the heating flue *z*, the

draught being in the direction opposite that of the platform, namely from the air inlet *i* to the waste gas outlet *k* (Fig. 5) and chimney flue *c*, the former being directly in front of the charging chute *g*¹.

The gas enters the flue *z* through ports *m*, more or less diametrically opposite the charging chute *g*¹ and considerably in advance of the air inlets *i* (Fig. 9); thus the portion of the flue between these points serves for preheating the air and at the same time cooling the material.

Immediately behind the charging chute *g*¹ is the device for removing the material. 15 This consists of a casing *n* containing a bucket conveyor *o* suitably driven from the shaft of pinion *f*², for instance, as indicated in Fig. 7. The front side of the casing carries a scraper plate *p*¹ which arrests the material contained in the trough and enables it to be picked up by the buckets of the conveyor and discharged into a horizontal air-tight worm conveyor *p* (Fig. 7) from which it is discharged by an air-tight rotary 20 25 vice *q*.

The furnace thus described in detail is airtight because it is intended for heating a material in an atmosphere of gas other than air. For supplying the gas to the muffle chamber there is provided a flue *r* above the heating flue *z* to which the gas is supplied through port *s*. From here it travels in direction opposite to that of the heating gas to short vertical flues *t* which connect the flue *r* with the interior of the muffle (Fig. 3). Passing through these into the muffle, the gas reverses its direction and travels to the outlet *u* where it leaves the muffle by passages *v*.

40 *w* is a heat insulating air-space.

At the part of the furnace where the material is charged and discharged there are preferably substituted for the roof of the muffle, removable plates *x* which permit of 45 inspection and repair of the surface of the platform.

Having thus described the nature of my said invention and the best means I know of carrying the same into practical effect, I 50 claim:—

1. A muffle furnace for producing chemical changes comprising a completely closed annular chamber, a travelling platform within the said chamber, means for charging material on to the said platform without interrupting the operation of the furnace and means for discharging the material from the platform without interrupting the operation of the furnace.

60 2. A muffle furnace for producing chemical changes comprising a completely closed gas-tight annular chamber, a travelling platform within the said chamber, means for charging material on to the said platform 65 without interrupting the operation of the

furnace and means for discharging the material from the platform without interrupting the operation of the furnace.

3. A muffle furnace for producing chemical changes comprising a completely closed 70 annular chamber, means for directly heating the roof only of the said chamber, a travelling platform within the said chamber, means for charging material on to the said platform without interrupting the operation 75 of the furnace and means for discharging the material from the platform without interrupting the operation of the furnace.

4. A muffle furnace for producing chemical changes comprising a completely closed 80 annular chamber, a travelling platform within the said chamber having its upper surface in close proximity to the roof of the chamber, means for directly heating the roof only of the said chamber, means for charging material on to the said platform without interrupting the operation of the furnace and means for discharging the material from the platform without interrupting the operation 85 of the furnace.

5. A muffle furnace for producing chemical changes comprising a completely closed 90 annular chamber, a travelling platform within the said chamber having its upper surface in close proximity to the roof of the chamber and of such cross section that the said surface is equidistant from the roof throughout the cross section, means for directly heating the roof only of the said chamber, means for charging material on to the 95 said platform without interrupting the operation of the furnace and means for discharging the material from the platform without interrupting the operation 100 of the furnace.

6. A muffle furnace for producing chemical changes comprising a completely closed annular chamber, a travelling platform within the said chamber adapted to carry the material in such a manner that the material does not touch the heated surface of the chamber, means for charging material on to the said platform without interrupting the operation of the furnace and means for discharging the material from the platform 110 without interrupting the operation of the furnace.

7. A muffle furnace for producing chemical changes comprising a completely closed 115 annular chamber, a travelling platform within the said chamber, a heating flue above the roof of the chamber, a flue above the said heating flue, ports for admission of gas into the latter flue, and communication between the latter flue and the interior of the chamber such that gas preheated by the heating flue can be passed into the chamber.

8. A muffle furnace for producing chemical changes comprising a completely closed 120 annular chamber, a travelling platform 125

within the said chamber, a flue above the roof of the chamber, a waste gas flue, a connection of the latter flue with the flue above the roof of the chamber, a device for feeding the material on to the said platform which device is placed near and behind the said connection in the direction of travel of the material in the chamber, gas inlets to the said flue above the chamber diametrically opposite to the said device and air inlets to the flue above the chamber near and behind the said device.

9. A muffle furnace for producing chemi-

cal changes comprising a completely closed annular chamber, a travelling platform 15 within the said chamber, means for charging material on to the said platform without interrupting the operation of the furnace, means for discharging the material from the platform without interrupting the operation 20 of the furnace and means for setting the discharging means so as to remove any desired thickness of the material.

In testimony whereof I have signed my name to this specification.

ARTHUR McDougall DUCKHAM.
